ATTYS

UNITED STATES PATENT OFFICE.

ALLEN LOOMIS, OF TOLEDO, OHIO.

OCTAVE-KEY MECHANISM.

Application filed September 14, 1921. Serial No. 500,483.

To all whom it may concern:

Be it known that I, ALLEN LOOMIS, a citizen of the United States, residing at Toledo, in the county of Lucas and State 5 of Ohio, have invented new and useful Improvements in Octave-Key Mechanism, of which the following is a specification.

The present invention relates to musical instruments of the wood wind type, and 10 particularly to an octave or register key mechanism adapted to oboes to enable the performer to place the notes emitted in either the lower, or the middle or the upper register. In this particular description of 15 instrument two holes additional to the tone holes and stoppers or covers to control them are provided near the mouth-piece end of the instrument, but at different distances from such end, of which one or the other 20 alone must be opened when certain notes in the middle and upper registers, respectively, are played, and both of which must be closed when notes are played in the lower register. These holes are of very small 25 diameter and are liable to become stopped by accumulation of water and other foreign substances. Oboe players experience more annoyance from this cause than from any other. To remove such obstructions the 30 player ordinarily applies his lips to the obstructed hole and sucks or blows; but before he can do so, he must remove the hole stopper from the body of the instrument far enough to leave a clear space 35 around the hole. The mechanisms previously used for controlling these octave hole stoppers have had to be disassembled more or less completely in order to permit removal of the stoppers to the necessary 40 distance.

The main objects of my invention are two-fold. First, to provide means for operating the octave or register hole stoppers more conveniently and to better effect than 45 is possible with the operating mechanisms previously used, and second to enable the stoppers to be easily moved aside from the holes far enough to permit application of the player's lips thereto without requiring 50 dismounting or disassembling of the mechanism. The first of these objects and the essential principles of the means which I

have devised for accomplishing it are stated and explained in my Patent No. 1,336,359 dated April 6, 1920, and entitled "Key mechanism for wood wind instruments." So far as that object and result are concerned, the invention herein described and claimed is substantially identical with the mechanism for the same purpose disclosed 60 in my prior patent.

The second main object is accomplished by the combination with a modified form of the octave key mechanism described in said patent of a connection between the 65 octave hole stoppers and the means by which such stoppers are pressed toward the body of the instrument, which is easily disengageable to permit the stoppers to be swung back entirely clear of the holes which 70 they respectively cover.

The manner in which these objects are carried into effect and the principles of the invention for which I seek protection broadly and in detail can be best explained in 75 connection with a description of a specific mechanism embodying the invention, and for the purposes of such description attention is directed to the drawings annexed to this specification which illustrate the form 80 of the invention at present preferred by me.

In said drawings:—

Figure 1 is a plan view of the mouth-piece end of an oboe showing my octave 85 key mechanism applied thereto.

Figure 2 is an elevation of the left side.

Figure 3 is a cross section taken on line 3—3 of Figure 2 looking in the direction 90 of the arrow.

Figure 4 is a view generally similar to Figure 2 but illustrating the position of the mechanism when the thumb key is pressed upon.

Figure 5 is a cross section on line 5—5 95 of Figure 4.

Figure 6 is a view generally similar to Figures 2 and 4 but showing the position of the mechanism when both controlling keys are pressed upon.

Figure 7 is a cross section on line 7—7 100 of Figure 6.

Figure 8 is a side view similar to Figure 2, but showing the stopper connecting

lever of the mechanism disengaged from its control arm and raised with the stopper clear of the body of the instrument.

Figure 9 is a cross section on line 9—9
5 of Figure 8.

Figure 10 is a fragmentary side view of the connecting lever.

Figure 11 is a cross section on line 11—11
10 of Figure 2.

Like reference characters indicate the same parts in all of the figures wherever they occur.

10 represents the body of an oboe in which there are two holes near the mouth-piece end, which holes are covered by stoppers 11 and 12. The stopper 11 is carried by an arm 13 which turns freely upon a pivot rod 14 mounted in supporting posts 15, 16 and 17. The other stopper 12 is carried by an arm 18 which is also mounted to turn freely on the same pivot rod and to which is fixed a sleeve 19 surrounding said rod. A key 20 is also made fast to the sleeve 19 and is thus rigid with the stopper 12. Said key is of that type which is capable of being pressed upon by the knuckle of the performer's finger and called a "spatule," but it may be of other construction and type as shown in my aforesaid patent.

30 A floating lever 21, connecting the stopper arms 13 and 18, has its fulcrum on a stud 22 carried by an arm 23 which is mounted to turn loosely on the pivot rod 14, but is made fast to a sleeve 24, to which also 35 is secured a second arm 25. The ends of the floating lever 21 are linked to the stopper carrying arms 13 and 18, preferably by means of pins or extensions 26, 27 (shown dotted in Figures 2, 4 and 6) on the ends 40 of the lever which enter complementary sockets in the adjacent stopper arms. These coupling extensions are so fitted as to permit free articulated movement of the stopper arms and floating lever about axes at right angles to one another, without objectionable 45 looseness otherwise.

A second pivot rod 28 is mounted in posts 29, 30 and 31 parallel to the rod 14 and thereon are rotatably mounted sleeves 32 and 33. The sleeve 32, between posts 30 and 31, carries an arm 34 which underlies the previously mentioned arm 25 and acts thereupon with the function of the machine element known as a wiper. Also attached 55 to the same sleeve is a key 35 which extends under the body of the instrument and is adapted to be pressed upon by the performer's left hand thumb.

60 The sleeve 33, which is arranged between the posts 29 and 30, is somewhat shorter than the distance between these posts and is adapted, therefore, to be moved endwise by the amount of this deficiency in length. It 65 carries in a rigid manner a presser arm 36 which extends toward the floating lever 21

and enters a socket 37 in the adjacent side of said lever. A needle spring 38 is fixed at one end in the post 30 and extends parallel to the sleeve 33, its other end being engaged with a hook 39 on said sleeve in a 70 manner common with instruments of this type. This spring exerts force yieldingly in the direction which causes presser arm 36 to press on the floating lever toward the instrument body 10; and it extends far enough toward the post 29 to insure that it will not become disengaged from the hook when the sleeve 33 is moved up to said post. A finger extension 40 is formed as a part 75 of the presser arm and is so arranged that upon being pressed toward the body of the instrument it will raise the presser arm; and also that it will act as a stop against the body of the instrument to prevent the presser being raised high enough to derange or permit derangement of the mechanism.

At the side of the socket 37 toward the instrument body is a ledge or abutment 41 (Figures 8 and 10) against which the end 80 of the presser arm is normally held by the spring; but disengagement of the presser arm from this abutment is made possible by means of a channel 42 running from the edge of the lever and entering the side of the socket. A shoulder 43 between the socket and the channel, and below the entrance from the channel to the socket, prevents accidental release of the presser from the socket. This channel is shown in the present drawings as cut in the side face of the lever part way through, but it may be formed as an open notch and the recess 37 may be a lateral extension of such notch, the abutment and shoulder then being a 85 hook-like projection bounding the under side of the extension. In effect the socket and its entrance channel form a bayonet joint slot from which the presser arm may be disengaged by first raising it clear of the shoulder between the abutment and channel and then moving it endwise toward the post 29. For thus raising the arm pressure is 90 applied toward the body of the instrument on the finger 40. Reengagement of the arm with the lever is effected by movements in the reverse order to that described.

When the presser arm 36 is coupled to the floating lever, as is the case when the instrument is being played, it is caused by the spring 38 to close both stoppers upon the octave holes, at the same time holding the key or spatule 20 in its depressed position, that is, the position nearest the body of the instrument and holding the thumb key 35 95 raised. By the term "raised" in connection with either of the keys or stoppers I mean the position in which they are displaced from the body of the instrument and from which they are adapted to be moved toward the body, regardless of the direction of such 100

displacement with respect to the horizontal plane; and the term "depressed" means in the same connection the position or movement of the key or stopper nearest to or toward the body.

For playing all notes in the lower register both stoppers must be closed; while for playing notes in the second register from G downward the hole covered by the stopper 12 must be opened, and for playing all notes above G in the second register, the hole covered by the stopper 11 must be opened. In each case where one of the octave holes is open, the other must be closed. When the thumb key 35 is pressed upon, the wiper 34, acting through the arm 25, sleeve 24 and arm 23, raises the fulcrum of the floating lever, and so raises the stopper 12, since the stopper 11 is held closed by the presser. The key 20 is then raised also, owing to its rigid connection with the stopper 12. If now, while the thumb key remains depressed, the key 20 is also depressed, the stopper 12 is closed and the floating lever 21 rocked about its raised fulcrum, raising the stopper 11.

The key 20 projects so far toward the tone hole key 44, which is worked by the first finger of the left hand, that it can be pressed upon by the knuckle of this finger while pressure is maintained by the finger tip on the key 44; whence both keys can be depressed at the same time by the same finger when required. But when key 44 needs to be raised, the finger can easily be slipped from that key over upon the spatule key without releasing the latter.

A valuable feature of the mechanism to which I make claim is that when the thumb key is released, the stopper 12 and spatule 20 are automatically depressed and retained so by the spring. This condition prevents any untoward effect following from pressure being unintentionally applied by the performer on the spatule when playing notes in the lower register, particularly in passing from G to A, which requires the third finger of the left hand to be raised. Due to the poor muscular control of that finger, the performer unconsciously rocks his hand when lifting it, but even though in doing so he should accidentally press on the spatule, neither octave hole would be affected unless the thumb key were depressed at the same time. Throughout the middle and upper registers the thumb key is depressed naturally by the thumb, which has no other task to perform, and the spatule is raised, or tends to be raised, by the spring 38, wherefore the same character of rocking of the performer's left hand in passing from G to A in the middle register causes the spatule to be depressed, which gives the result then desired of closing stopper 12 and raising 11.

When any obstruction gathers in either octave hole, the performer disengages the

presser from the floating lever in the manner previously described, which leaves the parts consisting of two stopper arms, the floating lever and the key 20 entirely free from connection with any other part of the instrument except the pivot rod 14, about which they are free to turn. They may then be turned back far enough to leave the octave holes clear for application to them of the player's lips.

Preferably a lock 45 is provided on the sleeve 33 and arranged to interlock with the arm 13 when the mechanism is swung back after the presser arm 36 has been disconnected from the floating lever. This lock is made as an arm or lug on the sleeve having a notch on its outer end which comes into the plane of the V-shaped rib 46 on arm 13 when the presser is disengaged from the floating lever. As appears from Figure 11 the rib 46 is cut away at the side which lies adjacent to the end of the locking member when the stoppers are closed, whereby it is possible to move the presser freely into and out of connection with the floating lever in the manner described. When the stoppers are swung back the rib and lug interlocking prevents the presser from being accidentally slipped back into a position which might possibly confuse the performer when attempting to reconnect it with the floating lever.

Various modifications in the mechanism herein described may be made without departing from the invention claimed herein; and also the novel features of the invention may be applied with or without modifications in form to any other instruments and uses which they are adapted to serve, within the scope of my claims. In all such instruments to which the principles of this invention are applicable, holes and stoppers equivalent to the octave holes and their stoppers hereinbefore described, are provided. For the purpose of more generic definition I prefer to designate such holes and the mechanisms for controlling them by the term "register."

What I claim and desire to secure by Letters Patent is:

1. A register key mechanism comprising two stoppers, a key engaged with one of said stoppers, a floating lever articulated to both of said stoppers, a second key operatively associated with said lever to raise and depress the fulcrum thereof, and a spring arranged to exert depressing force upon the second of said stoppers.

2. A register key mechanism comprising the combination with an instrument body having lateral holes of two stoppers covering two of said holes and mounted upon said body with capability of being raised and depressed, a lever engaged with both of said stoppers, a fulcrum support for said lever

mounted with capability of being raised and depressed, a spring acting upon said lever and at a point between said fulcrum and one of the stoppers and exerting force toward the body, a finger key having engagement with the other of said stoppers, and a second key arranged and cooperating with said fulcrum support to raise the latter when pressed upon.

- 10 3. A register key mechanism for woodwind instruments comprising the combination with an instrument body having tone holes and octave holes and a key for one of the tone holes, of two stoppers respectively 15 cooperating with the octave holes, an intermediate lever in articulated connection with both stoppers, a key connected with one of said stoppers and extending with near approach to said tone hole key whereby to be 20 operable by the same digit of the performer which operates said tone hole key, a spring arranged to apply stopper closing pressure upon the lever, a fulcrum support for said lever between the aforesaid specified octave 25 hole stopper and the point of application of said spring, and key operated means arranged and adapted to raise said fulcrum support under pressure from another of the performer's digits.
- 30 4. A register key mechanism for woodwind instruments comprising the combination with the instrument body having octave holes of two stoppers cooperative with said holes, spring means normally holding both 35 stoppers closed, and two keys coupled with both stoppers so arranged that when one key is pressed upon one of the stoppers only is opened, and when the second key is 40 pressed upon during maintenance of pressure on the first key, the other stopper is opened and the first opened stopper is closed.

5. A register key mechanism for woodwind instruments comprising the combination with the instrument body having two 45 octave holes, of stoppers respectively cooperating with said holes, a floating lever articulated to both stoppers, a movable fulcrum on which said lever is pivotally supported, a key connected with said fulcrum in a manner 50 enabling it to alter the distance of the fulcrum from the instrument body, when pressed upon, a second key connected with one of the stoppers, and spring means arranged to exert force tending to close said 55 stoppers.

6. In a wood-wind instrument having tone holes and octave holes, stoppers for the respective octave holes, a key connected to one of said stoppers and extending into 60 such proximity to one of the tone holes that it may be pressed upon by the knuckle of a finger whose tip is placed over said tone hole, a coupling member engaged with both of said stoppers, a second key, a spring organized to act on said coupling member, the

key being arranged to raise the coupling member between the stoppers when pressed upon and the spring arranged to exert force toward the instrument on the coupling member at a point between the second stopper 70 and the point at which the action of the second key is transmitted to the coupling member.

7. A key mechanism for wood wind instruments comprising two stoppers, a lever extending between said stoppers and articulated to both, a fulcrum support on which said lever is mounted and being arranged for swinging movement about the same axis with the stoppers, a spring actuated presser disconnectedly engaged with said lever arranged to apply force thereon toward the instrument body, a key, and a disengageable pressure transmitting member between said key and fulcrum support arranged to cause 80 raising of said support when the key is pressed upon.

8. In a musical instrument the combination with a hole stopper pivotally connected with the body of the instrument, of a presser having a detachable engagement with said stopper, a spring acting on said presser causing it to apply force on the stopper toward said body, a key, and a stopper lifter connected with said key and having engagement with the stopper which engagement is positive only in the direction away from said body, whereby upon disconnection of the presser from the stopper the latter is 90 left free to be swung away from the body.

9. A musical instrument having a lateral hole and a stopper pivotally mounted upon the body of the instrument to close and open said hole, and an operating mechanism for said stopper adapted to be readily disconnected therefrom whereby to permit wide swinging movement of the stopper away from the hole far enough to permit application of the player's lips thereto, said mechanism comprising a spring-pressed arm mounted on a different axis from that of the stopper and a key operated arm also on a different axis from that of the stopper, the first-named arm being arranged to apply force on the stopper toward the body and being laterally shiftable to a position wherein it is unable to apply such force, and the key operated arm being arranged to apply lifting force to the stopper and being otherwise unconnected therewith.

10. A musical instrument having a lateral tone hole and a stopper pivoted on the body of the instrument and movable to close and uncover said hole, a presser pivotally connected to said body on a different axis to that of the stopper and being also displaceable in the direction of said axis, a spring acting on said presser tending to move it toward the body, an abutment associated with the stopper arranged to receive the 110 115 120 125 130

- pressure of said presser when the latter is in one limit of its axial displacement and to be clear of the presser when the latter is in the opposite limit of such displacement, 5 and a key having means for raising the stopper but being otherwise unconnected therewith.
11. A key and stopper mechanism for wood wind instruments comprising a plurality of stoppers pivoted on substantially the same axis to the body of the instrument, a lever articulated to both stoppers, a fulcrum support carrying said lever and pivoted on substantially the same axis as 10 the stoppers, said lever having an interior abutment facing away from the body and an angular channel leading from one edge
- of the lever to said abutment, a presser arm pivotally mounted on an axis parallel to the previously mentioned axes and also being 20 movable lengthwise of its axis, said presser being adapted to pass through said entrance channel by virtue of pivotal and axial movements and come to bear on the abutment, a spring arranged to urge said presser to 25 ward the body, a key having an engagement with the fulcrum support for raising the latter and being otherwise disconnected from the stoppers and lever, and a second key rigidly connected with one of the stoppers.
- 15 In testimony whereof I have affixed my signature.

ALLEN LOOMIS.
